CLAIM

The ornamental design for a chuck for industrial robot, as shown.

DESCRIPTION

FIG. 1 is a front elevational view of a chuck for industrial robot showing our new design, the rear elevational view being a mirror image of the front view shown;

FIG. 2 is a top plan view thereof;

FIG. 3 is a bottom plan view thereof;

FIG. 4 is a left side elevational view thereof;

FIG. 5 is a right side elevational view thereof;

FIG. 6 is a top, front and right side perspective view thereof;
and,

FIG. 7 is a bottom, rear and left side perspective view thereof.
